UNITED STATES PATENT OFFICE.

GIBBARD RICHARD HUGHES, OF LONDON, ENGLAND.

PRINTER'S FORM OR CHASE RACK.

SPECIFICATION forming part of Letters Patent No. 703,264, dated June 24, 1902.

Application filed March 17, 1902. Serial No. 98,605. (No model.)

To all whom it may concern:

Be it known that I, GIBBARD RICHARD HUGHES, merchant, a subject of the King of Great Britain, residing at 77 Leadenhall 5 street, in the city of London, England, have invented a Printing Form or Chase Rack, of which the following is a specification.

This invention relates to a rack for holding printing forms or chases of varying sizes 10 and in such a manner as to prevent injury to the face of the type and friction between the sides of the forms or chases and the rack.

In the accompanying drawings, Figure 1 is a perspective view of a part of a form or chase 15 rack made according to this invention. Fig. 2 is a plan of one of the guiding-arms on an enlarged scale, and Fig. 3 is a modification of Fig. 1.

The same parts are lettered to correspond 20 in all the figures.

Referring to Figs. 1 and 2, to carry out my invention I form the rack by securing battens or fillets *a* parallel to each other onto the floor of the room or other receptacle *b* 25 for storing the forms *c*, as shown in Fig. 1, arranging these battens or fillets *a* so as to form or provide grooves or spaces *d* between them, the said fillets forming guides for the forms, and in said grooves or spaces *d* I mount 30 antifriction-rollers *e* to receive or carry the lower sides of the forms *c*. Onto the side of the wall or other convenient part of the room or receptacle *b* I fix, by suitable brackets or holdfasts *f* or equivalent means, a horizontal 35 rod or tube *g*, on which a number of sleeves *h* are separately and loosely mounted in positions corresponding to the floor-grooves *d* between the battens or fillets *a*. To each sleeve *h* is rigidly affixed an arm or rod *i*, 40 (see Fig. 2,) bifurcated at its free end to receive the top edge of the form or chase *c* and having an antifriction-roller *k* mounted at the fork of the bifurcation or thereabout. When the form or chase *c* is pushed into the 45 rack between the floor-grooves *d*, the corresponding arm or rod *i* will rest on the form or chase *c*, with its forked ends lying one on each side and its roller *k* on the top or upper side of said form. The arm or rod *i* being 50 fast on the sleeve *h*, which is free to turn on

the fixed horizontal tube or rod *g*, will rise or fall freely, according to the height of the form or chase above the ground.

In the modification shown in Fig. 3 horizontal and vertical antifriction-rollers *a'* and *e'* are mounted in or on a base-plate *b'*, the horizontal rollers *a'* forming the guides for the forms and being arranged so as to form between them a space *d'*, corresponding to the grooves *d* in Fig. 1, to receive the lower 55 side of the form or chase *c*. In this modification the horizontal rod or tube *g* is shown supported on standards *f'*, secured to the base-plate *b'*.

What I claim, and desire to secure by Letters Patent of the United States, is—

1. A printing form or chase rack comprising a base, guides carried by said base and between which the form is adapted to be guided, and an arm loosely mounted at one 70 end and adapted to engage at its opposite end with the upper edge of a form, in the manner and for the purpose specified.

2. A printing form or chase rack comprising a base, guides carried by said base between which a form is adapted to be guided, 75 antifriction-rollers carried by the base and adapted to take against the lower edge of the form, an arm loosely mounted at one end and forked at the opposite end and an antifriction-roller between the forks of the arm, all arranged for coöperation as and for the purpose specified.

3. A printing form or chase rack comprising a base, horizontal antifriction-rollers carried by the base and forming guides for the 85 form or chase, vertical antifriction-rollers carried by the base against which the lower edge of the form is adapted to bear, an arm loosely mounted at one end and forked at the opposite end, and an antifriction-roller between the forks of the arm, all arranged for coöperation as and for the purpose specified.

In testimony whereof I have hereunto set my hand, in presence of two subscribing witnesses, this 4th day of March, 1902.

GIBBARD RICHARD HUGHES.
